JOURNAL BOX

William T. Bissell, Indianapolis, Ind., assignor to
 Journal Box Servicing Corporation, Indianapolis, Ind., a corporation of Indiana

Application June 16, 1945, Serial No. 599,932

4 Claims. (Cl. 308—38)

1

This invention relates to railroad car journal boxes in general, and in particular relates to means for preventing "waste grabs" by the simple expedient of eliminating the diagonal pressure upon the waste in the box at the time the journal brass may be lifted when the car is subjected to sudden impact as frequently happens in railroad sorting yards where the cars are "humped."

In the standard construction, it is customary to support the weight of the car through a truck side frame resting upon or being a part of the journal box into which extends the journal of the car wheel axle, and then mount a brass over a limited portion of the top side of the journal. The construction permits relative upward travel of the journal box without restraint other than the weight of the car and the load carried thereby. Due to the inertia effect upon sudden stopping of the car, the car itself comes to a stop, but the mass of the wheels and trucks thereunder tend to move on with the result that when the side frames of the trucks are stopped, the wheel axle journals also tend to move on until they strike something to stop that movement.

In the construction heretofore employed in journal boxes, the journal shoulder back of the brass strikes the ribs on each side of the dust guard channel tending to batter down those ribs, as well as destroy the dust guard itself, all with the result that the journal tends to roll ahead from under the brass thereon. This rolling ahead action by reason of the curvatures of the under side of the brass and the top side of the journal sets up a component of force which actually lifts the brass and the journal box relative to the journal, causing the journal to compress the waste thereunder between the journal and the floor of the box. The direction of this compression is not vertically downwardly but diagonally rearwardly in relation to the relative travel of the journal toward the side of the box. The result of this diagonal downward pressure is a tendency to force the waste up around and between the journal and the side wall of the box, on that side of the journal brass which is then lifted from the journal, all with the frequent result that particles of the waste enter under that lifted side of the brass and are pinched or gripped between the brass and the journal when the journal comes to rest and the brass settles back down thereon under the weight of the car.

Thereafter, when the car is set in motion, the grabbed waste eliminates any ability to lubricate

2

the journal from the under mass of waste; the brass heats; and the babbitt actually melts and flows; all producing a condition requiring the car to be set out of the train if that condition is caught in time, otherwise the journal becomes unduly heated with the subsequent well known result. This heating action takes place very quickly, and such waste grabs while known to exist very frequently have not been recognized as due to the fact that there is an actual separation between the brass and the journal under the impact conditions above suggested.

It is the important object of this invention to eliminate the possibility of waste from entering between the brass and the journal due to any separating conditions, and to accomplish this result without adding any of the heretofore presented schemes of inserting members on each side of the journal in an attempt to hold down the waste. Such devices are ineffective under the extreme pressure produced by the lifting of the journal box relative to the journal. It is also an important object of the invention to provide a very simple device which may be utilized in the standard journal boxes without alteration thereof, and be replaceable when necessary. Further, it is an important object to provide such means that may be utilized readily without interfering with the normal procedure of replacing wheel axles as becomes necessary from time to time when wheel flanges wear or flat spots occur on the wheels. A decided advantage of the invention is found in the fact that damage to journal boxes is eliminated under the impact conditions. It has frequently been found to be the case that under some impacts, the sides of the journal box itself are actually bulged by impact of the journal thereagainst.

These and other objects and advantages of the invention will become apparent to those versed in the art in the following description of the invention as illustrated in the accompanying drawings, in which

Fig. 1 is a view in outer end elevation of a journal box (with lid open) embodying the invention;

Fig. 2, a vertical section on the line 2—2 in Fig. 1;

Fig. 3, a transverse vertical section on the line 3—3 in Fig. 2;

Fig. 4, a transverse vertical section on the line 4—4 in Fig. 2;

Fig. 5, a view in front elevation of the dust guard parts of the invention in associated relation;

Fig. 6, a view in perspective of one of the impact transmitting members of the dust guard; and

Fig. 7, a view in perspective of a dust guard illustrating a modified form of the invention.

Like characters of reference indicate like parts throughout the several views in the drawings.

In the illustrations herein employed, the journal box 10 is shown to be an integral part of the side frame 11. The journal 12 is inserted in the usual manner through an opening in the rear of the box 10 to extend by a portion within the box to receive the bearing 13 thereon with the wedge 14 thereover securing the bearing 13 in position, all in the usual and well known manner, this being the normal standard construction. Space is provided under the journal 12 and above the floor of the box 10 into which the usual oil saturated waste 15 is packed.

Back of the journal 12 is an enlarged diameter portion 16 on the car axle 17. This portion 16 is positioned to be that part of the axle 17 which extends through the rear end of the box 10. The opening through the box 10 is of a larger diameter than that of the portion 16 to provide clearance around that portion for relative shifting of the box 10 upwardly, particularly to permit removal of the bearing 13 for replacement or to permit removal of the journal 12 from the box, also necessitating lifting of the bearing to permit clearance over the outer end flange 18 of the journal 12. The relationship of the shoulder 16 to the opening, designated by the numeral 19 is best shown in Fig. 3.

In the rear wall of the box 10 through which this opening 19 appears, there is provided a dust guard receiving groove 20, Fig. 2. On the rear side of this groove 20, the opening 19 is defined by a substantially circular margin, whereas the inner side is defined by a substantially rectangular flange 21 having the corners rounded.

An impact member 22, Figs. 5 and 6, is designed to have an under supporting leg 23 terminating by a lower upturned foot 24. Then there is a body portion 25 continuing upwardly from the leg 23 to carry an impact head 26. The widths of the leg 23, foot 24, and body 25 are the same and are slightly less than the width of the groove 20 so that the member 22 may be fitted in that groove to have the body 25 back therein, and the leg 23 and foot 24 traversing substantially half of the lower part of the groove. The head 26 extends across the groove and is shaped to have its back sides bear against the margin of the hole 19, Fig. 3, on the outer rear side of the box, and also to bear against the vertical edge portions of the inner flange 21, Fig. 4. The rear sides of these portions of the head 26 extend across the two flanges defining the groove 20 therebetween, and are so proportioned as to bear against those flanges simultaneously with the back side of the body 25 bearing against the bottom of the groove 20. An identical member 22 is placed in the groove 20 on the opposite side, the feet 24 of the two members being brought into abutment at the lower end of the groove so as to prevent slipping downwardly of the members from their normally desired vertically disposed positions. These members 22 are further designed to have the central portions of the heads 26 substantially at the central horizontal diametrical plane of the journal 12.

The under dust closure member 27 is provided to have an upper surface curved to fit around substantially the entire under half of the jour-

nal 12, and is given a width to permit it to slide freely within the groove 20, at least by its under portion. Between the dust closure member 27 and the legs 23 of the members 22, are interposed some resilient means in order to resiliently urge the member 27 upwardly into sliding contact with the shoulder 16. In the particular form herein shown, Figs. 5 and 6, a leaf spring 28 is attached to the leg 23 adjacent the foot 24 on each of the members 22 to normally curve upwardly and outwardly against the under side of the member 27. To permit adequate travel of the member 27 within the channel of the groove 20, the underside of the member 27 is provided with a notch 29 in order to clear the two feet 24 thereunder should the journal box 10 happen to be lifted unduly relative to the journal 12.

A top dust closure member 30 is provided to enter the groove 20 from the top side of the box and drop down by gravity to have an under curved surface come into sliding contact with the upper half of the axle portion 16. In this respect, lower ends of the member 30 extend respectively downwardly over the inner sides of the impact heads 26, and in like manner upwardly extending side portions of the lower dust closure member 27 extend upwardly along the heads 26. However, these opposing ends of the two dust closure members 27 and 30 are spaced apart to permit the shoulder 16 to contact directly the impact heads 26 on either side, a very slight clearance being provided between the shoulder and these heads whereby the shoulder normally turns free of contact with those heads although the clearance therebetween is sufficiently close to prevent substantially entrance of dust and dirt into the box along the shoulder 16. As indicated in Fig. 5, the upper ends of the members 22 are stepped off from their outer sides to their inner sides, and under edge portions of the dust closure member 30 are correspondingly stepped to interfit therebetween so that there may be vertical travel of the member 30 relative to the impact members 22 and the member 30 still serve to keep the members 22 spaced apart. This is accomplished by having the vertical faces 31 and 32, Fig. 5, on the member 30 be in substantial sliding contact with the respective vertical faces 33 and 34 of the side members 22. Of course, the downwardly turned ends of the member 30 between the impact heads 26 further serve to maintain the setting of the members 22 in the groove 20.

Now should the car carrying the side frame 11 be subjected to sudden stoppage, the axle 17 will tend to move laterally of the box 10 in a direction depending upon the direction of impact. Since the journal 12 may travel but the slight clearance left between the impact heads 26 and the sides of the portion 16, there cannot be sufficient travel to cause the bearing 13 to be lifted upwardly since the bearing would normally have that amount of permissible travel within the box 10 in any event equal to the clearance between the journal and the impact heads 26. Even though the bearing 13 be absolutely stationary relative to the box 10, there still could not be sufficient lifting action of the bearing from the journal to cause any harm since the journal 12 cannot travel any distance causing downward pressure on the waste 15 and tending to "squirt" it around upwardly between the side of the journal and the side wall of the box into contact with the bearing edge.

In other words, the impact of the journal to-

ward the box is taken directly through the impact heads 26 and the back member 25 as well as through the flanges about the opening into the box. Therefore, the impact is taken directly through those members to the box 10, and no battering action can occur between the journal 12 and the box itself. Any hammering away of metal will come on the heads 26, and they may be replaced readily before being completely hammered away to permit the shoulder to come into contact with the flanges around the groove 20.

Referring to Fig. 7, the general contour of the dust guard, generally designated by the numeral 35, is that of the customarily employed dust guard fitting within the groove or slot 20 of the box 10. Normally this dust guard 35 is made out of wood and is free to slide vertically in the slot 20 of the box to follow the relative travel of the journal 12. Also, there is permitted lateral travel of the guard 35 within that slot 20 so that ordinarily the guard may function until there is excessive lateral travel of the journal 12, whereupon the guard becomes destroyed or at least crushed so that it no longer will follow the contour of the shoulder. In any event, it does not afford any resistance to relative travel between the journal 12 and the box 10. In this regard, the guard 35 may have sections 36 and 37 of metal inserted in each side thereof to carry the pressure of the shoulder 16 to the bottom of the slot 20 in case of tendency of the journal 12 to travel from its normal central position within the box to either side thereof. By reason of the presence of these insertions 36 and 37, they will tend to resist that relative travel. It is to be noted, however, that in order to permit the free functioning of the guard 35 to follow the shifting of the journal 12 relative to the box 10, only the back ends of the sections 36 and 37 may be brought into contact at the inner walls of the slot 20 to transfer the pressure from the journal thereto. In the form of the invention first above described, pressure is transmitted not only to the outer wall of the slot 20, but also to the peripheral flanges on each side thereof.

While the invention has been above described as being embodied in members separate from the journal box, it is obvious that the impact heads may be formed as integral parts of the box to take the axle impact directly therethrough to the box itself and still perform the same object, namely the elimination of the lifting of the bearing brass from the journal under inertia conditions arising from car impact or harsh brake action.

A further important advantage of the invention not above mentioned arises in the extension of the usable life of the bearing brass. When the brass is subjected to the impact of the journal, the brass is tended to be pounded by its central locating portion against the receiving lug on the side of the box, with the result that the brass ends are spread relative to the central section. Thus by arresting relative lateral travel of the journal in respect to the box, the journal cannot travel to roll under the brass edge to distort the brass.

While I have herein shown and described my invention in the forms as now best known to me, it is obvious that structural variations may be employed without departing from the spirit of the invention, and I therefore do not desire to be limited to those precise forms beyond the limitations as may be imposed by the following claims.

I claim:

1. For a railway car journal box having a groove opening inwardly around a rear box opening, through which the journal extends into the box, the groove being defined by and between spaced apart ribs extending vertically of the box on each side of the journal and around across thereunder, all in normally spaced relation from the journal, an impact head comprising an anvil head having a substantially vertical, planar outer face to be presented toward the journal; a body portion in the nature of a rib extending vertically across and fixed to the back of said head to fit slidably in said groove to bottom therein upon approximate contact of the back side of said head with the outer edges of said ribs; and a head supporting leg extending therebelow and curving around outwardly from the plane of said face to terminate approximately at the longitudinal, vertical, central plane of said box, the leg being formed to be slidably received within said groove; whereby said impact head may be inserted in said box with the journal therein by entering said leg in said groove to one side of the journal and dropping the head to allow the leg to slide around the groove under the journal and have the anvil head be located on the side of the journal to substantially fill in the space between that side of the journal and the groove ribs.

2. For a railway car journal box having a groove opening inwardly around a rear box opening, through which the journal extends into the box, the groove being defined by and between spaced apart ribs extending vertically of the box on each side of the journal and around across thereunder, all in normally spaced relation from the journal, an impact head comprising an anvil head having a substantially vertical, planar outer face to be presented toward the journal; a body portion in the nature of a rib extending vertically across and fixed to the back of said head to fit slidably in said groove to bottom therein upon approximate contact of the back side of said head with the outer edges of said ribs; and a head supporting leg extending therebelow and curving around outwardly from the plane of said face to terminate approximately at the longitudinal, vertical, central plane of said box, the leg being formed to be slidably received within said groove; whereby said impact head may be inserted in said box with the journal therein by entering said leg in said groove to one side of the journal and dropping the head to allow the leg to slide around the groove under the journal and have the anvil head be located on the side of the journal to substantially fill in the space between that side of the journal and the groove ribs; a second impact head duplicating the first described impact head to be inserted in said groove on the opposite side of said journal; and abutments on the free ends of said legs striking one another, thereby limiting the downward travel of each of said impact heads to central positions along the sides of the journal.

3. For a railway car journal box having a groove opening inwardly around a rear box opening, through which the journal extends into the box, the groove being defined by and between spaced apart ribs extending vertically of the box on each side of the journal and around across thereunder, all in normally spaced relation from the journal, an impact head comprising an anvil head having a substantially vertical, planar outer face to be presented toward the journal; a body portion in the nature of a rib extending vertically across and fixed to the back of said head to fit

slidably in said groove to bottom therein upon approximate contact of the back side of said head with the outer edges of said ribs; and a head supporting leg extending therebelow and curving around outwardly from the plane of said face to terminate approximately at the longitudinal, vertical, central plane of said box, the leg being formed to be slidably received within said groove; whereby said impact head may be inserted in said box with the journal therein by entering said leg in said groove to one side of the journal and dropping the head to allow the leg to slide around the groove under the journal and have the anvil head be located on the side of the journal to substantially fill in the space between that side of the journal and the groove ribs; a second impact head duplicating the first described impact head to be inserted in said groove on the opposite side of said journal; and abutments on the free ends of said legs striking one another, thereby limiting the downward travel of each of said impact heads to central positions along the sides of the journal; a lower closure member having a lower end portion at least slidable in said groove over said legs and having an upper portion entering by vertical edge portions between said heads below the central horizontal plane through said journal; and an upper closure member freely slidable by vertical edge portions in said groove on opposite sides of said box above said heads and having lower sections of those edge portions entering between said heads above said horizontal plane.

4. For a railway car journal box having a groove opening inwardly around a rear box opening, through which the journal extends into the box, the groove being defined by and between spaced apart ribs extending vertically of the box on each side of the journal and around across thereunder, all in normally spaced relation from the journal, an impact head comprising an anvil head having a substantially vertical, planar outer face to be presented toward the journal; a body portion in the nature of a rib extending vertically across and fixed to the back of said head to fit slidably in said groove to bottom therein upon approximate contact of the back side of said head

with the outer edges of said ribs; and a head supporting leg extending therebelow and curving around outwardly from the plane of said face to terminate approximately at the longitudinal, vertical, central plane of said box, the leg being formed to be slidably received within said groove; whereby said impact head may be inserted in said box with the journal therein by entering said leg in said groove to one side of the journal and dropping the head to allow the leg to slide around the groove under the journal and have the anvil head be located on the side of the journal to substantially fill in the space between that side of the journal and the groove ribs; a second impact head duplicating the first described impact head to be inserted in said groove on the opposite side of said journal; and abutments on the free ends of said legs striking one another, thereby limiting the downward travel of each of said impact heads to central positions along the sides of the journal; a lower closure member having a lower end portion at least slidable in said groove over said legs and having an upper portion entering by vertical edge portions between said heads below the central horizontal plane through said journal; and an upper closure member freely slidable by vertical edge portions in said groove on opposite sides of said box above said heads and having lower sections of those edge portions entering between said heads above said horizontal plane; and resilient means spacing said lower closure member from said underlying legs.
